TAP SWITCH

Roy H. Olson, Marion, Iowa, assignor to Collins
Radio Company, a corporation of Iowa

Application October 2, 1942, Serial No. 460,559

7 Claims. (Cl. 200—11)

This invention relates to a tap switch, and more particularly to a switch operating on the same general principle as a fan switch, but having its taps arranged around a center in an arc exceeding a semicircle.

One feature of the invention is that it enables an arrangement of the taps in an arc approaching a full circle; another feature of this invention is that it enables unused portions of the element connected to the taps to be shorted despite the fact that the contact arc is greater than a semicircle; yet another feature of this invention is that it enables a given number of taps to be arranged in an arc of smaller radius, or with greater spacing between taps, highly desirable in transmitting equipment where high voltages are being handled; other features and advantages of this invention will be apparent from the following specification and the drawing, in which:

Figure 1 is a side elevational view of a switch embodying this invention; Figure 2 is a view along the line 2, at right angles to the view of Figure 1; Figure 3 is a view similar to Figure 2, but with the contact arms rotated somewhat, this view showing one of the contact arms moving up an incline leading from one plane of rotation to a different plane of rotation; Figure 4 is a sectional view along the line 4 of Figure 1; Figure 5 is a fragmentary detailed view showing the inclined portion of the displacement member, the other portion being broken away; Figure 6 is a schematic diagram of the operation of the device shown; and Figure 7 is a schematic diagram illustrating the principle of operation of a switch of this type.

Certain electrical elements are frequently associated with a tap switch for varying the amount or portion of said element which is active in the circuit to which it is connected. One example of this is an inductance coil in radio apparatus, either transmitting or receiving, such a coil being frequently associated with a tap switch to enable its inductance to be varied, in steps, from minimum to maximum. Since the unused portion of the coil has distributed capacity, it is necessary at higher frequencies to short the unused or inactive portion of the coil. Moreover, this shorting cannot be done at higher frequencies by a mere connection across the entire unused or inactive portion since the points of shorting connection must be close enough together to prevent self-resonance at the frequencies being handled.

Means for properly shorting parts of the inactive portion of the coil as the active portion is

varied is known and in use, such an arrangement being termed a fan switch. Its principle of operation is illustrated in Figure 7, where a coil 10 is shown having its ends connected by leads 11 and 12 to some other circuit element with which it cooperates, as for example, a condenser. Taps 13a-i are provided, these being connected to the coil at equally spaced points; and switch members 14a-i are adapted to cooperate with these taps. These switch members 14 are interconnected mechanically and electrically, as is indicated schematically, and movement of the switch member assembly upwards (speaking with respect to the position of the parts shown in Figure 7) step-by-step results in varying the active portion of the coil while maintaining the inactive portion shorted with connections sufficiently close together to prevent any difficulties with self-resonance even at high frequencies. For example, if the switch member assembly is moved up two steps until switch member 14a engages tap 13c, it will be seen that that portion of the coil lying between 13a and 13c will be active in the circuit, while the remaining portion lying between 13c and 13i will be inactive and shorted at a plurality of points.

While this arrangement is very satisfactory from an electrical standpoint, its embodiment in actual switch structure has heretofore been limited to apparatus where the taps were arranged around the center in an arc not exceeding a semicircle, since the contact arms had to have an inactive arc, to which they could move, equal in size to the arc in which they were arranged. This space limitation resulted in unduly limiting the number of taps which could be used, or requiring an arc of excessively large radius. The present invention obviates this difficulty and enables the taps and contact arms to be arranged in an arc closely approaching a full circle, so that the same number of taps with the same spacing can be arranged in a circle of about half the diameter of that heretofore required.

Referring now more particularly to Figures 1-5, a coil 15 is shown having a tap switch associated therewith at one end. Taps 16a-i are arranged about a center coaxial with the shaft 17, the upper or contacting surfaces of the taps lying in a plane and in an arc closely approaching a full circle, this arc being considered as having one end starting at 16a and as having its other or terminal end at 16i. The taps are electrically connected in conventional manner to the turns of the coil at similarly spaced intervals, as shown in Figure 1.

A switching arrangement is carried by and rotatable with the shaft 17, this arrangement including switch arms 18a-e, these being shown in Figure 2 as having their contacting tips in the same plane as the surfaces of the taps 16, the arms being so arranged as to contact every other tap. It will be understood that this is a matter of choice, the number of taps being determined by the number of steps of inductance which are desired and the number of taps between switch arms being determined by the amount of coil which can be bridged before self-resonance takes place at the frequencies being handled. In order to keep one end of the coil always connected to the circuit regardless of the position of the switch arms, variation taking place at the other end of the coil, tap 16i is connected by a strip 19 to the contact ring 20 engaged by brushes 21a-c, electrically and mechanically connected to the switch members.

As may be best seen in Figures 2-5, the insulating member 22 in which the taps are mounted serves not only as a bushing for the shaft 17 but also as means for supporting a displacement member 23, this member having an inclined portion 23a and a plane portion 23b which is concentric with the shaft 17 and in a plane parallel to but spaced from that of the contacting surfaces of the taps. The displacement member 23 is mechanically attached to the member 22 in any convenient means, but with the point of attachment or support outside of the arc in which the contact arms 18 move, as may be best seen in Figure 4.

When the switch arms are in the position shown in Figure 2, they coincide with the arrangement schematically shown in Figure 6, all of the coil being shorted out and none of it being active. When it is desired to render part of the coil active, the shaft 17 is rotated clockwise (speaking with respect to the parts as shown in the drawing), as by the knob 24. A rotation of approximately 90° brings the parts into the position shown in Figure 3, where the arm 18e is shown as having passed up the inclined portion 23a and now riding on the upper surface of the portion 23b of the displacement member, the arm 18d being shown moving up the inclined portion. This view was chosen to illustrate the way in which the contact arms move from the contact plane to the displaced plane, but it will be understood that rotation will be continued until the contact arms stop on a desired tap, as for example, with the arm 18a on the tap 16d, when the portion of the coil between the taps 16a and 16d would be active. The displacement is possible, of course, because of flexibility in the spring metal arms 18; and it will be apparent that it is only by moving these arms to a different plane that they can be caused to pass over part of the tap arc without causing undesired effects. If it were not for this displacement, for example, when arm 18a was on tap 16d, arm 18d would be on tap 16a, and none of the coil would be active. The inclined portion must lie in the space between the ends of the arc in which the taps are arranged, and the size of this space and the amount of space between the two planes is determined by the voltages to be handled and the possibility of arcing difficulty, just as this same factor determines the permissible spacing between the taps.

While I have shown and described certain embodiments of my invention, it is to be under-

stood that it is capable of many modifications. Changes, therefore, in the construction and arrangement may be made without departing from the spirit and scope of the invention as disclosed in the appended claims.

I claim:

1. A switch of the character described, including: a set of contact members arranged around a center in an arc exceeding a semicircle; another set of contact members arranged around said center and adapted to make engagement with the members of the other set; means for rotating one of said sets with respect to the other; and means for moving at least some of said members to and maintaining them in a different plane during said rotation.

2. A switch of the character described, including: a set of separate contact members arranged around a center in an arc exceeding a semicircle; another set of contact members arranged around said center, this set being interconnected and adapted to make engagement with the members of the other set; means for rotating one of said sets with respect to the other; and means for moving at least some of said members to a different plane during said rotation.

3. A switch of the character described, including: a set of contact members having their contacting surfaces in a plane and arranged around a center in an arc exceeding a semicircle; a set of cooperating contact members having their contacting surfaces in said plane and arranged around said center; means for rotating one of said sets with respect to the other; and means for moving at least some of said contacting surfaces out of said plane during said rotation.

4. A switch of the character described, including: a set of contact members having their contacting surfaces in a plane and arranged around a center in an arc exceeding a semicircle; a set of interconnected contact arms having contacting surfaces arranged in the same plane and arc; means for rotating the arms around said center; and means for moving the contacting surfaces on said arms out of said plane when the rotation would otherwise cause undesired contacts.

5. Apparatus of the character claimed in claim 1, wherein the last mentioned means is operative on a contact after it has left one end of said arc and before it reaches the other end.

6. Apparatus of the character claimed in claim 4, wherein the last mentioned means comprises a member having a portion in a plane spaced from but parallel to the first mentioned plane and an inclined portion leading from one plane to the other.

7. A switch of the character described, including: a plurality of taps having their contacting surfaces in a plane and arranged around a center in an arc exceeding a semicircle but less than a full circle; a set of interconnected contact arms having their tips arranged at the same distance from said center as said surfaces and movable in the same plane; means for rotating the arms around said center; and a member having a portion overlying said taps in a plane spaced from but parallel to the first mentioned plane and an inclined portion leading from one plane to the other, this portion being in the space between the ends of said arc, whereby rotation of said tips causes them to move from one plane to the other after leaving one end of said arc.

ROY H. OLSON.
